UNITED STATES PATENT OFFICE.

JOHN A. HUGHSON, OF NEW YORK, N. Y.

TOBACCO PIPE.

Application filed August 18, 1923. Serial No. 653,019.

To all whom it may concern:

Be it known that I, JOHN A. HUGHSON, a citizen of the United States, residing at New York, in the county of New York and State of New York, have invented a certain new and useful Tobacco Pipe, of which the following is a specification.

This invention relates to improvements in pipes and is more especially directed to a pipe wherein the smoke passage may be kept free from deposits of nicotine and saliva through the employment of an associated sump in which such saliva and nicotine are adapted to be trapped.

16 The invention is more especially characterized by the construction wherein both the stem of the bowl and the mouth piece are provided with a liner in the form of a removable tube, intermediate the ends of which is associated an integral sump. The liner tube with its associated sump may be removed from the pipe parts for cleaning and the sump preferably contains a short length of pipe cleaner, the absorbent characteristics of which cause the saliva and nicotine to be taken up by the cleaner. When the pipe is cleaned the cleaner is removed and thrown away and a new one positioned in the sump.

30 The advantage of the foregoing construction is that no smoke, saliva or nicotine come into contact with the bore of the stem or mouth piece, and consequently these parts are kept sweet and clean.

35 Other features of advantage will be apparent from the following detailed description when read in conjunction with the accompanying drawings and the appended claims.

40 The accompanying drawings illustrate one practical embodiment of the invention, but the construction therein shown is to be understood as illustrative, only, and not as defining the limits of the invention.

45 Figure 1 is a section of a pipe embodying this invention, the parts being shown in assembled relation.

Figure 2 shows the pipe parts dismantled and the liner and sump removed.

50 Figure 3 is a perspective view of a liner and sump with the cleaner removed.

Figure 4 is a section on the line 4—4 of Figure 3.

55 Referring to the drawings, 1 designates the bowl of the pipe, having a suitable stem 2 with which is associated a mouth piece 3.

The bowl, stem and mouth piece may be of any suitable material or shape as these features constitute no part of the present invention.

60 The stem 2 is provided with a bore 4 and the mouth piece 3 is provided with an aligned bore 5, so that a liner tube 6 can be received within these bores collectively, when the parts are assembled and the liner tube, as shown in Figure 3, may, in practice, be in the form of a metal tube of sufficient length to reach from the hollow in the bowl to the distant end of the mouth piece when the parts are assembled as shown in Figure 1. 70 This tube is, however, adapted to have a sliding fit with the bores 4 and 5, so that, when the mouth piece is removed, the tube can be removed from both the mouth piece and the stem 2.

75 Associated with the tube 6 and adjacent the end thereof which occupies the stem 2 is a sump 7. This sump may be conveniently formed from a short length of tubing similar to the tubing 6 and is welded, soldered 80 or otherwise secured to the tube 6 in a substantially line contact therewith and in parallel relation thereto. Along this line of contact the walls of the two tubes are cut away forming a communicating slot 8, as 85 best shown in Figure 4, and this slot extends an appreciable distance longitudinally of the tube 7 as shown in Figure 1, but not for the full length of this tube.

90 The stem 2 is cut away to provide a supplemental bore 9 to receive the sump 7 as shown best in Figures 1 and 2, and the parts are so proportioned that when they are removed, the bowl end of the bore or passage 9 will close the corresponding end of the 95 sump while the opposite end of the sump will be closed by the end of the mouth piece.

100 It will be apparent that with a pipe so constructed, nicotine, saliva or other liquid or semi-liquids passing through the liner tube 6 will gravitate through the slot 8 and into the sump 7, so that such extraneous materials will be trapped out and will not enter the mouth of the smoker or the bowl of the pipe.

105 The parts are normally assembled for use as shown in Figure 1, where, it will be noted, the liner tube 6 extends the full length of the smoke passage so that, as the smoke traverses this passage, it does not come into contact with either the stem 2 or the mouth piece 3. Nicotine, saliva and other extra-

neous matter accumulate in the cleaner 10 positioned in the sump and the pipe remains clean and sweet for a long period. At suitable intervals, however, the parts should be 15 dismantled as shown in Figures 2 and 3 for the purpose of removing and discarding the small absorbent cleaner section 10. This can be readily accomplished because of the fact that both ends of the sump are open. An 20 ordinary pipe cleaner may, at the same time, be passed through the liner tube 6 to thoroughly clean it, and, after a new section of cleaner is positioned in the sump, the parts 25 of the pipe may be reassembled to prepare it for further use.

It will thus be manifest that the pipe of this invention may be readily maintained in a clean and sanitary condition and that the drawing of nicotine from the bowl of the 20 pipe into the smoker's mouth, as has heretofore been a common occurrence, is entirely obviated. I consider the possibility of renewal of the liner tube for the purposes of 25 cleaning, highly important and advantageous as it permits a thorough cleaning of the parts. I further consider the use of a liner tube substantially coextensive with the smoke passage of considerable importance, since the parts of the pipes are not 30 subjected to contact with saliva or impurities.

The accompanying drawings show the invention in its preferred practical form, but this invention is to be understood as 35 fully commensurate with the appended claims.

Having thus fully described my invention, what I claim as new, and desire to obtain by Letters Patent is:

40 1. A tobacco pipe embodying a bowl, a stem associated with the bowl and provided with a smoke passage, and a mouth piece associated with the stem and also having a smoke passage, in combination with a liner 45 tube extending substantially the full length of the combined smoke passages of the stem and mouth piece, and a sump associated with the liner tube intermediate its ends and communicating with the interior of the liner tube, said sump being housed in concealed position within the pipe.

2. A tobacco pipe embodying a bowl, a stem associated with the bowl and provided with a smoke passage, and a mouth piece 55 associated with the stem and also having a smoke passage, in combination with a liner tube extending substantially the full length of the combined smoke passages of the stem and mouth piece, a sump associated with the liner tube intermediate its ends and communicating with the interior of the liner tube, said sump being housed in concealed position within the pipe, and absorbent ma-

terial positioned within the sump and adapted to collect the liquid and semi- 65 liquids entering the sump.

3. A tobacco pipe embodying a bowl, a stem associated with the bowl and provided with a smoke passage, a mouth piece detachably associated with the stem and also having a smoke passage, in combination with a liner tube extending substantially in full length of the combined smoke passages of the stem and mouth piece, and a sump associated with the liner tube intermediate its 70 ends and communicating with the interior of the liner tube, said liner tube and sump being removable from the stem and mouth piece to facilitate cleaning, when the mouth piece is detached from the stem. 80

4. A tobacco pipe embodying a bowl, a stem associated with the bowl and provided with a smoke passage, a mouth piece detachably associated with the stem and also having a smoke passage, in combination with a liner tube extending substantially in full length of the combined smoke passage of the stem and mouth piece and a sump associated with the liner tube intermediate its 85 ends and communicating with the interior of the liner tube, said liner tube and sump being removable from the stem and mouth piece to facilitate cleaning, when the mouth piece is detached from the stem, and absorbent material positioned within the sump 90 and adapted to collect liquids and semi-liquids entering the sump, said absorbent material being removable from the sump when the liner tube and sump are detached from the stem and mouth piece. 95

5. A tobacco pipe embodying a bowl, a stem associated with the bowl and provided with a smoke passage, and the mouth piece associated with the stem and also having a smoke passage, in combination with a liner tube extending substantially the full length of the combined smoke passages of the stem and mouth piece, a sump extending longitudinally of the liner tube for a distance less than the length of the tube and provided with the passage communicating with the interior of the liner tube, the opposite ends of the sump being open, and absorbent material within the sump, the opposite ends of the sump being adapted to be closed by abutting portions of the stem and mouth piece when the parts are in assembled relation, and the liner tube and sump being removable from the stem and mouth piece to facilitate cleaning and removal of the absorbent material, when the mouth piece is removed from the stem. 105 110 115

In testimony whereof I have signed the foregoing specification.

JOHN A. HUGHSON.
